(57) **CLAIM**

The ornamental design for conduit joining apparatus, as shown and described.

DESCRIPTION

FIG. 1 is a perspective view of a first embodiment of the conduit joining apparatus of my design;

FIG. 2 is an exploded perspective view thereof;

FIG. 3 is a front elevational plan view thereof;

FIG. 4 is a right side elevational view thereof, the left side elevational view being a mirror image thereof;

FIG. 5 is a top plan view thereof;

FIG. 6 is a bottom plan view thereof;

FIG. 7 is a partial cross-sectional view thereof taken along line 7—7 of FIG. 3;

FIG. 8 is a perspective view of a second embodiment of the conduit joining apparatus of my design;

FIG. 9 is an exploded perspective view of FIG. 8;

FIG. 10 is a front elevational plan view of FIG. 8;

FIG. 11 is a right side elevational view of FIG. 8, the left side elevational view being a mirror image thereof;

FIG. 12 is a top plan view of FIG. 8;

FIG. 13 is a bottom plan view of FIG. 8; and,

FIG. 14 is a partial cross-sectional view of FIG. 8 taken along line 14—14 thereof.

The broken line showing is included for the purpose of illustrating portions of the article that form no part of the claimed design.
